UNITED STATES PATENT OFFICE

THOMAS J. KENT, OF SAN FRANCISCO, AND HERBERT P. BELL, OF OAKLAND, CALIFORNIA, ASSIGNORS TO EAST BAY STREET RAILWAYS, LTD., OF OAKLAND, CALIFORNIA, A CORPORATION OF CALIFORNIA

DESIGN FOR A TOKEN

Application filed January 19, 1931. Serial No. 38,354. Term of patent 14 years.

To all whom it may concern:

Be it known that we, THOMAS J. KENT and HERBERT P. BELL, citizens of the United States, residing at the city and county of San Francisco, State of California, and city of Oakland, county of Alameda, and State of California, respectively, have invented a new, original, and ornamental Design for Token, of which the following is a specification, reference being had to the accompanying drawing, forming part thereof.

Fig. 1 is a plan view of a token showing our new design.

Fig. 2 is an edge view of the token.

The token is an embossed metal coin of about the size of a five cent piece and the design of both sides is alike, except that the lettering on the reverse side reads "Good for One Fare".

We claim:

The ornamental design for a token substantially as shown and described.

THOMAS J. KENT.
HERBERT P. BELL.
